COKING OR CRACKING OF OILS, PITCHES,
AND THE LIKEJulius Geller, Bad Homburg, vor der Höhe, Germany,
assignor to Rutgerswerke-Aktiengesellschaft, Frankfurt am Main, Germany

Application October 27, 1950, Serial No. 192,587

3 Claims. (Cl. 202—121)

For coking petroleum residues, brown and hard coal pitch and the like, comparatively large quantities of this initial material are coked in correspondingly spacious devices or ovens. In one known process, the petroleum residues are first of all heated in a tube-type oven and then coked in several parallel-arranged oven chambers constructed of refractory bricks. These chambers are heated from below by means of a large number of burners. Owing to the high content of volatile constituents in the petroleum residues, it is only possible to fill up the oven chambers slowly and gradually, so that the charging time lasts altogether 2 hours. When the filling has been completed, the oven chambers are heated from about 500° or 600° up to about 900° or 1000° C. The coking process itself lasts about 3 hours. Before the expiry of this period, the temperature of the oven is gradually reduced again to about 500°.

For emptying the chambers the ovens have doors, and these are lifted after the coking is finished. As the coke is deposited in large adhering pieces in this process, considerable difficulty is experienced in removing it from the oven. So as to facilitate this removal, strong steel cables are placed in the oven chambers before charging these, the said cables being only partly covered by the filling material. On the completion of the coking and the removal of the oven doors, these steel cables are cooled with water and then connected with a winch. Through the forces produced by the winch the closely adhering lump of coke is broken up, and by this means the emptying of the oven chambers becomes possible.

In another known process, ordinary coke ovens are employed such as are usual in the coking of hard coals. Only minor alterations are made in the construction in order to make them suitable for the case under consideration. Although the capacity of these coke ovens is much greater than that of those previously described, the time needed for the actual working is several times that needed in the former instance.

The oven is emptied in the same manner as in normal type ovens, that is, through a pushing or pressing machine which is adapted to travel at the sides close to the ovens and the rod of which presses the coke out of the chambers on the doors being raised.

The known process has the disadvantage that the output is comparatively limited on account of the very long working time. In addition, the arrangement is subjected to considerable variations of temperature owing to the discontinuous operation and the large amounts filled into the chambers each time. These changes in temperature occasion corresponding heat expansions, and these lead after a short period of operating to cracks and leaks in the masonry. The said arrangements thus require constant overhauling and attention. The operating costs are also comparatively high.

A further disadvantage of the said processes is that the pitch coke is deposited in comparatively large, solid pieces. Now the coke is generally required for purposes where it has to be in small pieces, or even in a fine form, and the lumpy coke has therefore in all these cases to be ground fine at considerable expense.

In order to obtain the coke in fine pieces, the initial material has also been injected in a finely distributed condition in the presence of a flame and coked. An adequate fineness of grain is supposed to be obtained here. By injecting the material in nozzles, a great fineness of the grain may certainly be obtained, but this still leads

2

to an uneven end product, because the material is not injected in uniform masses and forms, and does not have a uniform impact.

5 The purpose of the invention is to obviate the disadvantages of the known processes. For this purpose the material is supplied to the coking space continuously in comparatively small amounts in a form as uniform as possible.

10 In order to obtain this the material to be coked is supplied to the coking space in the form of drops, streams or jets or flat sheets of a given thickness. The material is heated and coked in the shortest possible time, so that correspondingly high outputs are possible.

15 One specially effective form of the new method consists in guiding numerous simultaneous and uniform jets or sheets of material into the coking chamber, to traverse this latter in free drop or fall. Since the coking of the already preheated material ensues in the shortest possible time, the coking chamber does not require to be specially high in order to give the necessary drop. If, in accordance with the invention, the material is injected upwards from below into the coking chamber, the time the material is spending in the chamber is doubled. In such a case, the height of the arrangement can be further limited.

20 The material will be heated directly or indirectly according to the conditions of working and the properties of the material to be treated. If direct contact of the material, and of the vapours it develops, with the smoke or flue gases, has to be prevented, only indirect heating of the coking material can be employed. In many cases, however, direct heating is possible. In such cases the process may be effected at high pressure, as the casing which has to bear the pressure can be protected by a sufficiently strong inside insulation from the high working 25 temperatures.

30 Direct heating of the material becomes specially simple if part of the material itself is burned inside the coking chamber. In general, if the arrangement is adequately insulated, only about 4 to 8% of the material is required in order to carry out the cracking or coking operation at about 1000 to 1200° C.

35 Should it not be desirable for the working material and the vapours liberated therefrom to come into contact with the smoke or flue gases, even in such a case direct heating of the arrangement may still take place, only in this event the heating of the arrangement and the coking of the material must alternate regularly with one another. Thus the arrangement is first brought to the requisite working temperature by direct heating, and then the heating is cut off. The material is thereupon supplied to the coking chamber until the temperature of this latter has reached a certain low level; thereupon heating of the apparatus takes place once more, and so on.

40 As, in the new process, the material is coked in a comparatively finely distributed form, a uniformly fine-grained coke is deposited possessing a large surface area. Consequently the coke has to be cooled off, on leaving the arrangement, in the absence of air, with steam or cold flue gases, to such a point that it cannot ignite 45 during its subsequent contact with the air.

45 Should the traversing period provided for the material not be enough to obtain a complete liberation of the volatile constituents, further provision has been made, in accordance with a preferred form of the invention, to subject the depositing coke to a special or additional treatment immediately following. To this end a tunnel kiln can be directly connected on, or it is treated in a collecting hopper in the suspended state, either with 50 superheated steam at approximately 1000° C. or with smoke or flue gases from burners, or by furnace-type burners.

55 For carrying out the new process, vertical and preferably cylindrical coking chambers with one or more preferably vertical supply pipes for the material are used. An outlet is also provided for the coke, and also an outlet for the gases liberated, the vapours being in general drawn off at the top and the coke at the lower part. Should the vapours still be carrying fine coke 60 particles along with them, it may be an advantage to pass the vapours, after their egress from the coking space,

through a cyclone, and to pass the separated particles of coke to the lower coke outlet.

If the material is heated indirectly, the coking chamber is surrounded by a casing spaced evenly and at a comparatively small distance from the former, so that an annular space is formed between the two for the passage of the heating gases. A simple constructional form of the arrangement is thus possible, providing a free and unrestricted heat expansion.

In order to supply and lead away the smoke or flue gases, collector channels are located both at the upper end and at the lower end of the annular gap. But as the hot fresh gases coming from the burner are supplied unsymmetrically to the collector channel, and as furthermore the outlet openings for the escape are in general arranged unsymmetrically, throttle grids are located between the collector channels and the annular gap for the purpose of equalising the one-sided draught. These throttle grids consist of movable constructional elements so as not to affect the free movability of the casing with respect to the coking chamber.

If the arrangement is constructed for a direct heating of the material then only one collector channel has to be provided at the upper or lower end of the coking space for conducting away the gases and liberated vapours. In this case also a throttle grid is provided between the coking chamber and the collector channel in order to equalise the one-sided draught during the conducting away of the gases and vapours.

As the material passes through the coking chamber in a free fall, the heat transmission by radiation must be correspondingly high. For this purpose, the walls of the coking chamber are in general heated to over 1000°. In addition, however, the inside walls of the coking chamber are preferably provided with a ceramic lining, containing admixtures of heavy metal oxides. In this way the radiating capacities of the inside walls are still further enhanced.

In order to utilise the perceptible heat of the gases and vapours leaving the apparatus, the combustion air, and also the material, are preheated to a considerable extent. In addition to this, further exhaust heat still existing can be used for other purposes.

The enclosed drawing shows in vertical longitudinal cross section an arrangement for cracking or coking with indirect heating of the coking space or chamber 1.

The embodiment consists essentially of a vertical cylinder which is closed at the bottom by means of a cone, the apex of which is directed downwards. At the top the cylinder terminates in a freely supporting cupola. The walls of the coking chamber consist of refractory ceramic material on account of the high working temperatures, which are generally over 1000° C. The material which is to be coked or cracked passes through a pipe 2 into a space 1, the pipe opening into a nozzle 3 directed vertically upwards. Through this nozzle the material is injected a considerable distance upwards into the coking chamber. The degree of breaking up of the material can be adapted to the prevailing conditions.

The cylindrical walls of the coking chamber 1 extend downwards beyond the cone so that an annular channel 4 is formed between the cone and the walls. One or more gas or oil burners 5 are connected to this channel and effect the heating of the whole arrangement. The bottom of the annular channel 4 is supported by an iron base plate 6, which in its turn is supported by a number of pillars 7. In this manner the coking chamber can expand freely and unrestrictedly in an upward direction from the base plate 6.

The coking chamber 1 is surrounded by a casing 8 for guiding the heating gases, this casing being provided with inside insulation 9. At the same time this insulation is so close to the coking chamber 1 that only a comparatively narrow annular gap 10 exists between the two parts. The hot smoke gases leaving the burner flow through the annular channel 4 and pass through openings 11 into the annular gap 10. The openings 11 are so dimensioned in cross section that in spite of a one-sided or unsymmetrical arrangement of the burner or burners 5, an even distribution of the smoke gases over the annular gap 10 is secured. In this way the walls of the coking chamber are swept in a completely uniform manner by the gases along the entire circumference and are thus heated in a completely uniform manner.

The insulation 9 embraces the external cylindrical wall surface of the coking chamber 1 at the lower end in the manner of a stuffing box, so that the two parts can expand independently during the heating. The corresponding annular slot between the two walls is preferably completely sealed in a gas-tight manner by means of asbestos cord or the like.

As may be seen in the drawing, the inside lining 9 of the casing 8 rests upon a base plate 12, which in its turn is supported by pillars 13. In this way the coking chamber and the surrounding casing are supported independently of one another.

The cupola closing the coking chamber at the top is provided with a centrally located branch 14 through which the vapours and gases that are released during coking or cracking can pass off.

The gases flowing upwards in the annular gap 10 pass finally into an annular collector channel 15, the bottom of which is formed by bricks 16. These bricks lie loosely on ledges of the inside insulation 9 and the branch 14, and they are formed with openings 17 of different sizes for the passage of the gases. The gases are conducted away from the collecting channel 15 by a branch pipe 18. Since a one-sided draught is present in this case, the openings 17 are calibrated in such a manner that the gases are drawn off from the gap 10 uniformly around the whole circumference.

The annular channel 15 is closed at the top by means of a cover 19, this latter having an inside insulation of suspended brick. The branch 14 provided for the outlet of the vapours is made gas-tight by means of a stuffing box 20 located on the cover 19, so that it is impossible for extraneous air to pass into the heating-gas system. A free expansion of the branch 14 in relation to casing 8 is thus made possible at this point also.

The coke dropping in the form of fine grains reaches an outlet branch 21 and is carried away by a worm 22, which is self-sealing against the passage of gas. Although the cone that closes the coking chamber at the bottom is not heated at the lower part, it is nevertheless of advantage to make the worm of heat-resistant steel or ceramic material.

In order to prevent the ignition of the still glowing coke in the air, it is first of all drawn off into a cooling chamber, and only then is it brought into contact with the air.

For the purpose of liberating the volatile constituents still retained in the coke, a calcining or graphiting plant not shown in the drawing is provided, which may consist of a tunnel kiln, and in which with uniform heating the volatile constituents are freed. The procedure may however be such that the coke occurring is held suspended in a hopper in an ebullient condition, and in this condition is treated with superheated steam or smoke gases from burners or by means of surface burners.

I claim:

1. A device for coking and cracking oils, pitches and the like, comprising in combination a vertical, cylindrical heating chamber; at least one conduit for the introduction into the middle zone of said chamber, of the material to be treated; said heating chamber having a downwardly tapering lower end part forming an opening for the discharge of residual products and being provided at its upper end part with a tubular outlet for the discharge of volatile products formed in the heating chamber; a cylindrical casing provided with a thermally insulating layer on its inner side and surrounding the wall of the heating chamber to form a narrow annular gap therewith, the upper end part of said casing surrounding the tubular outlet of the heating chamber and forming therewith an annular collecting channel for heating gases, said channel having a discharge opening for used heating gases, the bottom wall of the channel being formed by perforated elements arranged above said annular gap; the wall of the heating chamber extending downward around its tapering end portion and forming an annular second channel with the latter; said second channel being provided with at least one opening for burners supplying heating gases; said second annular channel being connected with said annular gap by openings having cross-sections of different size in order to equalize distribution and velocity of the heating gases supplied by said burners, within the annular gap; said elements forming the bottom wall of the collecting channel having perforations of different size, in order to equalize velocity of the heat-

ing gases passing from the annular gap to the collecting channel and to its discharge opening; said heating chamber and said casing provided with an insulating lining, being supported independently from each other and capable of thermal expansion independently from each other.

2. A device for coking and cracking oils, pitches and the like, comprising in combination a vertical cylindrical heating chamber; at least one conduit for the introduction into the middle zone of said chamber, of the material to be treated; said heating chamber having a downwardly tapering conical lower end part forming an opening for the discharge of residual products and being provided at its upper end part with a tubular outlet for the discharge of volatile products formed in the heating chamber; a cylindrical casing provided with a thermally insulating layer on its inner surface and surrounding the heating chamber to form a narrow annular gap therewith, the upper end part of said casing surrounding the tubular outlet of the heating chamber and forming therewith an annular collecting channel for heating gases, said channel having a discharge opening for used heating gases, the bottom wall of said channel being formed by perforated bricks loosely arranged at the upper end of said gap; the cylindrical wall of the heating chamber extending downward around its tapering end portion and forming an annular second channel with the latter; said second channel being provided with at least one opening for burners supplying heating gases; said second annular channel being connected with said annular gap by openings having cross-sections of different size in order to equalize distribution and velocity of the heating gases supplied by said burners, within the annular gap; said

bricks forming the bottom wall of the collecting channel having perforations of different size in order to equalize velocity of the heating gases passing from the annular gap to the collecting channel and to its discharge opening; said heating chamber and said casing provided with an insulating lining, being supported independently from each other and capable of thermal expansion independently from each other.

3. A device as claimed in claim 1, in which the casing has a ceramic lining containing the oxide of a heavy metal in order to increase the radiating capacity of the lining.
